UNITED STATES PATENT OFFICE

2,589,634

APPARATUS FOR LAYING CONCRETE

Charles H. Shook, Dayton, Ohio

Application December 23, 1949, Serial No. 134,740

9 Claims. (Cl. 61—63)

1

This invention relates to a method and apparatus to form a concrete ground slab and concurrently establish a determined grade in the slab.

The apparatus of this invention is particularly adaptable to laying of the concrete ground slab of large drainage lines such as those used in sanitary or storm sewer systems, or in laying the ground slab of large open top drainage ditches or irrigation ditches. When building large drainage lines carrying fluids it is desirable that the ground or floor slab for the line shall have all parts thereof drain toward the center of the line so that all fluids carried in the line will attain a determined velocity even though the flow in the line be a mere trickle. It is also necessary that the ground or floor slab shall have an established declining grade from one end of the line to the other to maintain a determined flow through the line.

In the past much manual labor has been required to establish a predetermined grade and ground form to receive a concrete ground slab or floor for a drainage line. Since the ground is used as one side of a form on which the slab is poured, the ground surface must be accurately developed in establishing both the grade for the line and the cross-sectional form to obtain a ground slab or floor that is of uniform thickness throughout its length and width.

It is therefore an object of this invention to provide a method and an apparatus for laying a concrete ground slab or floor for a drainage line that greatly eliminates need for manual labor in establishing the grade and cross-sectional shape of the ground forming the under-surface of the form for the ground slab.

It is another object of the invention to provide a method and an apparatus which can recurrently make checks of the grade and ground form to determine low spots or high spots in the ground form or in the grade.

It is another object of the invention to provide a method and apparatus for laying a concrete ground slab to a uniform thickness while concurrently forming the upper surface of the ground slab to a desired contour.

It is another object of the invention to provide a method and apparatus for the purposes of the foregoing object wherein the concrete ground slab or floor of a drainage line is provided with short vertically positioned side walls formed concurrently with the forming of the ground slab or floor.

It is another object of the invention to provide an apparatus to form a concrete ground slab

2

or floor of a drainage line wherein the floor is produced with the use of set forms, and wherein a short vertical wall is formed concurrently with the ground slab between wall forms, a part of which is movable to permit removal of the forms from the slab upon setting the concrete.

Another object of the invention is to provide an apparatus to perform the purpose of the foregoing object wherein the wall form for the vertical side wall is used to form the side walls concurrently with the ground slab or floor and provide means for establishing the grade for the drainage line, the wall forms supporting the apparatus that forms the contour of the upper surface of the floor of the drainage line.

Other objects and advantages will become apparent from the drawings and the following description.

Figure 1 is a perspective elevational view illustrating the apparatus of this invention in use in forming the ground slab or floor of a drainage line.

Figure 2 is a cross-sectional view of a part of the apparatus illustrated in Figure 1 showing a removable form in which a vertical section is formed concurrently with the forming or shaping of the floor slab of the drainage line.

Figure 3 is a cross-sectional view of a part of the apparatus illustrating the mechanism for troweling the floor slab.

Figure 4 is a cross-sectional view of a part of the mechanism illustrating the use of the mechanism in concurrently rough forming the upper surface of a floor slab and troweling thereof.

Figure 5 is a perspective view of the side wall form illustrated in Figure 2.

Figure 6 is a cross-sectional view of the apparatus illustrating its use in establishing the ground contour line to be used as the lower formed surface for the concrete ground slab.

Figure 7 is an enlarged cross-sectional view of a portion of the mechanism shown in Figure 6 illustrating the feeling rods which indicate correct ground surface contour.

Figure 8 is a side elevational view of the apparatus illustrated in Figure 1.

Figure 9 is a perspective view of a portion of the mechanism illustrating the manner of holding a copper plate in position during pouring of the concrete ground slab.

Figure 10 is a cross-sectional view taken along line 10—10 of Figure 2.

Referring to the drawings, the apparatus consists of a carriage 10 that supports a rough forming blade 11 and a troweling blade 12 so that as

the carriage 10 is moved longitudinally along the form tracks 13 and 14, the lower edge of the rough forming blade 11 will form the upper surface of a concrete ground slab or floor of a drainage line and concurrently therewith the troweling blade 12 which follows the rough forming blade 11 will trowel smooth the surface of the ground slab formed by the rough forming blade 11.

The carriage 10 consists of a pair of I beams 15 and 16. The I beam 15 is supported upon a pair of wheels 17 while the I beam 16 is supported upon a similar pair of wheels 18.

Uprights 19 and 20 extend from the I beam 15 while similar uprights 21 and 22 extend from the I beam 16, these uprights being of I beam construction.

The uprights 20 and 22 are inter-connected by horizontal angle bars 23 and 24, and similar angle bars 25 and 26 join the uprights 19 and 21. The uprights 19 and 20 are joined at their upper edges by the angle bar 27, and a similar angle bar 28 joins the upper ends of uprights 21 and 22. Also, the uprights 19 and 20 are inter-connected by an X frame 29, a similar X frame not shown, joining the uprights 21 and 22.

Diagonally placed angle bars 30 and 31 are provided between the angle bar 24 and the uprights 20 and 22 at the front side of the carriage while similar angle bars 32 and 33 are provided at the rear wall of the carriage.

The forming blade 11 positioned at the front wall of the carriage is suspended from the lower end of three angle bars 34, 35 and 36, the upper ends of which are attached to the horizontal connecting bars 23 and 24 of the forward wall of the carriage. The support bars 34 and 36 for the forming blade 11 are spaced inwardly of the uprights 20 and 22 whereby to provide channel openings 37 and 38 adapted to pass over wall forms 39 and 40, hereinafter described.

The troweling blade carried on the rear wall of the carriage 10 is similarly supported by the angle bars 41, 42 and 43, the bars 41 and 43 being spaced inwardly of the uprights 19 and 21 in the same manner as the bars 34 and 36 are spaced from the uprights 20 and 22, thus providing a clear channel which can move over the wall forms 39 and 40.

The forming blade 11 consists of a flat metal plate 45 that is reinforced by angle bars 46 and 47 at the upper and lower edges thereof and by other angle bars 48 extending vertically of the plate 45, all bars 46, 47 and 48 being placed on the rear face of the plate 11. Bolts 49 extend between the angle bar 47 of the plate 11 and an angle bar 50 secured to the lower ends of the support member bars 34, 35 and 36, to support the forming blade 11 from the carriage. Spacer members may be located in the space 51 between the angle bars 47 and 50, see Figure 4, to provide for a slight amount of vertical adjustment of the blade 11 so as to position it accurately with reference to a ground surface beneath the lower edge of the blade 11.

The lower edge 52 of the forming blade 11 is shaped to the contour desired to be placed in the upper surface of the ground slab or floor of a drainage line, and as shown in the drawings, this lower edge takes the shape of a V form.

The troweling blade 12, more particularly shown in Figures 3 and 4, consists of a flat troweling blade 60 having the same V shaped contour as the lower edge 52 of the forming blade 11. The trowel blade 60 is reinforced

transversely by plates 61 and longitudinally by a plate 62, thus giving rigidity to the flat blade 60. The forward edge 63 of the blade 60 is provided with a taper on the under side thereof, and a corresponding taper is provided on the rear edge 64 of the blade 60.

The troweling blade 12 is supported from an angle bar 65 that is attached to the lower ends of the support bars 41, 42 and 43, as shown in Figure 3, by means of rods 66. The lower ends of the rods 66 are suitably secured to the reinforcing plates 61, and the upper ends of the rods are threaded to receive the nuts 67 positioned on opposite sides of the ledge formed by the angle bar 65. The threaded rods 66 thus provide means for adjusting the troweling blade 60 vertically relative to the carriage 10 so that the under surface of the blade 60 can be positioned exactly level, or slightly below the level of the edge 52 of the forming blade 11, thus providing for a troweling action of the blade 60 on the surface of the ground slab or floor of the drainage line being laid as the carriage moves thereover.

One or more reinforcing bars 70 extend between the forward wall of the carriage 10 and the troweling blade 12 to maintain the same in a rigid vertical position. The reinforcing bar or bars 70 have their ends attached to the troweling blade 12 by means of bolts 71 extending through slots 72 provided in the end of the reinforcing bar 70 and in the plates 61. The slots just mentioned permit vertical adjustment of the troweling blade assembly 12 relative to the carriage 10, and relative to the support bars 70.

Similar support bars 75 extend between the rear wall of the carriage 10 and the forming blade 11 to rigidly support the same, and similar bolted connections 76 may be provided.

A pair of angle bars 80 and 81, see Figure 1, extend between the angle bars 26 and 24, which in effect provide the upper wall of the carriage 10 together with the bars 27 and 28. The angle bars 80 and 81 support a hand operated winch 82 from which extends a cable 83 that is used to move the carriage 10 along the form tracks 13 and 14 in a manner hereinafter described.

The side wall forms 39 and 40 cooperate with the carriage 10 and provide the means to support the carriage in its movement over the ground when forming the ground slab. The wall forms 39 and 40 are constructed alike so that only one of them need be described, these wall forms being more particularly illustrated in Figures 2 and 5 in which the wall form 39 is illustrated.

The wall form 39 consists of an angle bar 90 that has a foot 91 bent at right angles to the bar 90. Angle bars 92, 93 and 94 are suitably connected together so as to form a quadri-lateral having the angle bar 93 spaced a determined distance from the bar 90. An angle bar 95 is welded to the angle bar 90 parallel thereof as shown in Figures 1 and 10, and the bars 90 and 95 are rigidly secured relative to the foot 91 by means of a gusset plate 96.

A heavy wooden timber 97, for example a 3" x 10" timber, receives a plurality of the supports formed by the bars 90 and 95, the feet 91 of the supports being secured to the timber 97 by bolts 98, or lag screws. These supports are positioned in regular spaced relationship along the length of the timber 97. Between each adjacent pair of supports, short side wall timbers 100 and 101 are placed. These timbers are secured at one end to the support bar 95 by means of bolts 102 and at the opposite end to the sup-

port 90 by means of bolts 103 whereby the timbers 100 and 101 between the supports are joined together by the supports throughout the length of the wall. The quadri-laterals formed by the members 91, 92, 93 and 94 of the respective supports are joined together by means of an angle bar 105 suitably welded to each of the supports. The angle bars 90 and 95 are joined together by an angle bar 106 that also provides the form track 13, or the form track 14 to support the carriage 10, as illustrated in Figure 1.

With the carriage 10 supported upon the form tracks 13 and 14, the I beams 15 and 16 are positioned closely adjacent the quadri-laterals of the wall forms 39 and 40 so that the quadri-laterals guide the carriage upon the form tracks 13 and 14, and prevent the same from running off the tracks. The forward edges of the I beams 15 and 16 are provided with inside tapered surfaces 107 and 108 respectively to take care of any slight variation in position of the carriage between one form support and another.

As shown in Figure 2 the timbers 100 and 101 form the outer form wall of a vertical wall form. The inner wall of the vertical wall form is provided by a wooden timber 110 that is secured to the lower end of the angle bars 111 which are pivotally carried on the members 93 of each of the wall form supports by means of pivot bolts 112. The inner wall form 110 is thus movably supported relative to the outer wall form consisting of the timbers 100 and 101 so that after the vertical wall formed between wall forms is set, the wall forms can be readily removed from the concrete wall. To lock the inner wall form 110 in the position illustrated in Figure 2 a lock pin 115 passes through holes provided in the member 93 and the angle bars 111.

When forming the ground slab 125 of a drainage line together with the short vertical wall 125a, it is desired to provide a metal seal which will extend from the ground slab 125 into the upper vertical wall portion to prevent fluid leakage between the joint between the ground slab and the upper wall portion of the drainage line. To support a copper metal strip in position to function as a seal strip at the joint between the floor slab and the upper wall portion of the drainage line, brackets 130 and 131 extend downwardly from each of the members 94 of the wall form supports to which there is attached wood strips 132 and 133 respectively between which there is placed a copper strip 134 held in position by nails 135.

Also, the wood strips 132 and 133 have their outer walls tapered as indicated at 136 and 137 respectively to form a recess in the ground slab 125 which forms a groove into which concrete from the upper wall section will flow upon pouring of the upper wall section and thereby form a tongue on the upper wall section to prevent shifting of the upper wall section relative to the floor slab 125.

The wall forms 39 are provided with an angle plate 138 at each end thereof having a hole 139 to receive bolts for securing together adjacent wall form sections.

When establishing the grade and contour of the ground that is to provide the lower form wall of the ground slab, a series of feeler pins 140 are suspended through openings 141 provided in the lower angle bar 46, see Figures 4 and 7, of the rough forming blade 11. By moving the carriage 10 over the form tracks 13 and 14, the feeler pins 140 will indicate high and

low spots in the ground contour which can then be removed or filled in according to need.

In using the apparatus of this invention to produce a ground slab or floor of a drainage line, the ground at the proper drainage line level is graded to the desired drainage grade to receive the timbers 97 of the wall forms 39 and 40. This drainage grade is accurately established, as it determines the drainage grade of the upper surface of the ground slab.

Wall forms 39 and 40 are then set in their proper transversely spaced relationship and in parallel position relative to one another, with the timbers 97 resting on the drainage grade previously established. Stake pins 150 are then driven into the ground to hold the wall forms 39 and 40 in place. The carriage 10 is then placed upon wall form tracks 13 and 14, and the apparatus is ready to function. To move the carriage 10 along the wall forms 39 and 40, the cable 83 is attached at its free end to a timber, not shown, that may rest upon the wall forms 39 and 40 between the supports formed by the angle bars 92, 93 and 94 so that turning of the winch 82 will cause the carriage to be drawn forward over the wall forms 39 and 40 on the tracks 13 and 14.

The ground surface form 160 is finished in any suitable manner at a depth below the lower edge 30 of the forming blade 11 to establish the desired thickness of the ground slab. The contour of the ground surface 160 shall be the same as the contour of the lower edge of the forming blade 11 to obtain a uniform thickness transversely of 35 the ground slab. To insure uniformity of thickness in the ground slab, the feeler fingers 140 are first moved over the ground surface 160 after it has been rough formed to indicate high spots and low spots which can be cut off or filled in 40 accordingly.

When the contour of the ground surface 160 has thus been established, the feeler fingers 140 are removed from the forming blade 11. Thereafter, the concrete is poured onto the ground in 45 front of the forming blade 11 in sufficient quantity to form a ground slab of the desired thickness.

The carriage 10 is then moved forward by 50 manual rotation of the winch by workmen standing in the carriage 10. Forward movement of the carriage causes the forming blade 11 to cut the batch of concrete 170, see Figure 4, in front of the forming blade and cause the upper surface of the ground slab to be formed to the contour of the lower edge of the forming blade. Workmen will shovel concrete from the batch 55 in front of the forming blade into the vertical wall forms 39 and 40 to fill them to the upper edge of the wood strips 132 and 133, thus forming a short vertical wall section with the seal strip embedded therein as shown in Figure 2.

As the carriage 10 is advanced, the troweling blade 60 moves over the upper surface of the wall slab 125 to trowel the surface smooth. After 60 passage of the troweling blade 60 over the upper surface of the ground slab 125, any manual finish troweling can be applied to the surface, if such is desirable.

When the concrete has set, the wall forms 70 39 and 40 can be removed by merely pulling pins 115 from their locking position and pivoting the inner wall form 110 about the pivot pin 112. This opens up the form and permits it to be removed readily from the short vertical wall section produced between the wall forms. The nails

135 must of course first be removed from the wood strips 132 and 133 so that removal of the wall form 39 will leave the copper seal strip 134 in place in the vertical wall section 125a of the ground slab 125.

While the apparatus disclosed and described herein illustrates a preferred form of the invention and method of practicing the invention, yet it will be understood that alterations can be made without departing from the spirit of the invention, and that all modifications that fall within the scope of the appended claims are intended to be included herein.

Having thus fully described my invention, what I claim as new and desire to secure by Letters Patent is:

1. Apparatus for forming the ground slab of a drainage line including, wall forms positioned in spaced parallel relationship, each of said wall forms comprising an outer wall including track means carried by the outer wall, support means forming a part of said outer wall and projecting to one side thereof opposite that of said track means on the said wall, an inner wall supported by said support means in spaced relationship to said outer wall and having the lower edge thereof positioned above the lower edge of said outer wall a distance equal to that required to establish a predetermined thickness of a ground slab, a quadrilaterally arranged carriage frame having rollers supporting the frame on said track means for movement therewith, a supplemental frame structure supported on said carriage frame and having structural members at each side of said support means whereby to straddle said support means, a forming blade for working the fluid concrete suspended beneath said supplemental frame and carried on the innermost of said structural members thereof with the side edges of said blade adjacent said inner wall in close proximity thereto with the lower corner edges of said blade positioned at the level of the lower edge of said inner wall, and guide means included with said support means above said track means providing means to guide said carriage along said track means.

2. Apparatus for forming the ground slab of a drainage line including, wall forms positioned in spaced parallel relationship, each of said wall forms comprising an outer wall including track means carried by the outer wall, support means forming a part of said outer wall and projecting to one side thereof opposite that of said track means on the said wall, an inner wall supported by said support means in spaced relationship to said outer wall; a quadrilaterally arranged carriage frame having rollers supporting the frame on said track means for movement therewith, a supplemental frame structure supported on said carriage frame and having structural members at each side of said support means whereby to straddle said support means, a blade for working fluid concrete suspended beneath said supplemental frame and carried on the innermost of said structural members thereof with the side edges thereof adjacent said inner wall, and guide means included with said support means above said track means providing means to guide said carriage along said track means.

3. An apparatus for forming the ground slab of a drainage line, a wall form consisting of, an outer wall, support means forming a part of said outer wall and projecting to one side thereof, an inner wall pivotally connected to said sup-

port means for movement of the inner wall relative to said outer wall and including means for locking said inner wall in spaced relationship to said outer wall, and a supporting foot means extending from said outer wall on the side thereof opposite to that of said inner wall for supporting the wall form.

4. An apparatus for forming the ground slab of a drainage line, a wall form consisting of, an outer wall, support means forming a part of said outer wall and projecting to one side thereof, an inner wall pivotally connected to said support means for movement of the inner wall relative to said outer wall and including means for locking said inner wall in spaced relationship to said outer wall, a supporting foot means extending from said outer wall on the side thereof opposite to that of said inner wall for supporting the wall form, and track means carried by said outer wall on the side thereof opposite to that of said inner wall and above said foot support means.

5. An apparatus for forming the ground slab of a drainage line, a wall form consisting of, an outer wall, support means forming a part of said outer wall and projecting to one side thereof, an inner wall pivotally connected to said support means for movement of the inner wall relative to said outer wall and including means for locking said inner wall in spaced relationship to said outer wall, a supporting foot means extending from said outer wall on the side thereof opposite to that of said inner wall for supporting the wall form, and spaced bracket means carried by said support means intermediate said outer and inner walls each supporting a part of wedged strip extending longitudinally parallel with said inner and outer walls, whereby to provide for placement of a metal strip between said inner and outer walls and in spaced parallel relationship thereto.

6. An apparatus for forming the ground slab of a drainage line, a wall form consisting of, a longitudinally extending outer wall, a longitudinally extending foot support for said outer wall, projecting from one side thereof, support means positioned periodically along the length of said outer wall and including means securing said outer wall and said foot support thereto, said support means extending over the top of said outer wall and projecting from one side thereof opposite to that of said foot support, and a longitudinally extending inner wall positioned in spaced parallel relationship with said outer wall and including means pivotally connecting the same to said projecting support for movement of the inner wall relative to the outer wall and further including means for locking said inner wall in spaced relationship to said outer wall.

7. An apparatus for forming the ground slab of a drainage line, a wall form consisting of, a longitudinally extending outer wall, a longitudinally extending foot support for said outer wall projecting from one side thereof, support means positioned periodically along the length of said outer wall and including means securing said outer wall and said foot support thereto, said support means extending over the top of said outer wall and projecting from one side thereof opposite to that of said foot support, and a longitudinally extending inner wall positioned in spaced parallel relationship with said outer wall and including means pivotally connecting the same to said projecting support for movement of the inner wall relative to the outer wall and

further including means for locking said inner wall to said support means to maintain said inner wall in a fixed spaced relationship to said outer wall.

8. An apparatus for forming the ground slab of a drainage line, a wall form consisting of, a longitudinally extending outer wall, a longitudinally extending foot support for said outer wall projecting from one side thereof, support means positioned periodically along the length of said outer wall and including means securing said outer wall and said foot support thereto, said support means extending over the top of said outer wall and projecting from one side thereof opposite to that of said foot support, a longitudinally extending inner wall positioned in spaced parallel relationship with said outer wall and including means pivotally connecting the same to said projecting support for movement of the inner wall relative to the outer wall and further including means for locking said inner wall to said support means to maintain said inner wall in a fixed spaced relationship to said outer wall, and bracket means carried by said support means intermediate the inner and outer walls supporting longitudinally extending filler strips maintained in spaced parallel relationship to each other and in spaced parallel relationship to said inner and outer walls.

9. An apparatus for forming the ground slab of a drainage line, a carriage consisting of, a pair of longitudinally extending support members including wheels for supporting the same, connecting vertically positioned frame members at each

end of said support members frame members joining said vertically positioned frame members, other vertically disposed frame members connected with said connecting members at the forward and rearward side of said carriage and positioned inwardly of the carriage relative to said first vertically positioned frame members, said other frame members at the forward side of said carriage being connected at their lower ends with a forming blade having the side edges thereof positioned inwardly of and in spaced relationship to said longitudinally extending support members, and said other frame members at the rearward side of said carriage being connected at their lower ends to a troweling blade having the side edges thereof positioned inwardly of and in spaced relationship to said support members, all parts of the troweling surface of the said troweling blade being positioned in horizontal alignment with the corresponding lower edge surface of said forming blade.
